UNITED STATES PATENT OFFICE.

WILLIAM M. CAVANAUGH, OF NEW YORK, N. Y.

METHOD OF MAKING LEATHER YARN AND ARTICLE.

1,415,313.

Specification of Letters Patent.

Patented May 9, 1922.

Application filed October 15, 1918. Serial No. 258,210.

To all whom it may concern:

Be it known that I, WILLIAM M. CAVANAUGH, a citizen of the United States, and a resident of the borough of Richmond, city of New York, county of Richmond, and State of New York, have invented certain new and useful Improvements in Methods of Making Leather Yarn and Article, of which the following is a specification.

10 The invention relates to leather manufactures and particularly to the forming of leather into yarn.

The invention is particularly adapted for utilizing comparatively small flat strips of 15 leather in forming leather yarn. This yarn is made from short flat strips of leather which are joined—end to end—so as to form a long continuous flat length resembling a wide band and thereafter the continuous flat 20 length of leather thus joined, to wit, the said wide band, is split longitudinally into a series of long flat narrow strips each of which narrow strips is consequently made up of connected end-to-end pieces of leather, and

25 which pieces correspond in number to the pieces in the wide band, and thereafter the long flat narrow strips are wound so as to form a round product which is herein properly termed a leather yarn. As the winding 30 progresses the product is deposited upon a spool but before being spooled it is preferably intermittently rolled transversely in a manner to slightly twist the product and in a manner to tighten the winding and so as 35 to set the wind or twist by the operation of roll pressing.

As showing a specific manner in which the invention may be realized reference is made to the accompanying drawings forming a 40 part of this specification, in which drawings,

Figure 1 is a plan or face view of a portion of a long continuous flat length formed of pieces of leather joined end to end.

Figure 2 is a side or edge view of the 45 band shown in Figure 1.

Figure 3 shows in vertical elevation a pair of slitting rolls which can be employed to cut or slit the long band into a number of long flat narrow strips, each of the desired width.

Figure 4 shows the rolls in transverse section and in this figure there are also indicated several narrow flat strips as they appear immediately after the severing operation takes place and as the narrow strips are being wound or coiled upon spools.

Figure 5 is a plan view of a machine which may be employed for the winding or twisting of the narrow continuous strips into the circular product, herein termed yarn. In 60 this machine there is shown a winding head for forming the yarn, a mechanism for spooling the yarn, and mechanism for transversely rolling and twisting the yarn prior to its being spooled.

Figure 6 is a face view of a portion of the long narrow flat strip. In this figure the product is shown somewhat enlarged as compared with the strip usually employed, although it will be understood that a strip of 70 this width could be employed if desired.

Figure 7 is a view showing a portion of the yarn which is formed from the strip shown in Figure 6. In Figure 7 there is also shown a thread or strand which provides 75 a core for the yarn, if a core is desired, and in this figure there is indicated the manner in which the strip is wound or twisted—about the core—to provide the circular product herein termed the yarn.

Figures 8, 9 and 10 illustrate a woven fabric which can be formed from the yarn made in the apparatus herein shown. Figure 8 is a face view of the fabric, Figure 9 is a view taken on the plane as indicated by the line 9—9, Figure 8, looking in the direction of the arrows, and Figure 10 is a view taken on the plane as indicated by the line 10—10, Figure 8, looking in the direction of the arrows. Figure 10, however, 90 shows the fabric before it has been calendered or flattened; Figures 8 and 9 illustrate the fabric after it has been calendered or flattened.

Figure 11 is a view taken as on the plane 95 indicated by the line 11—11 of Figure 12 looking in the direction of the arrows.

Figure 12 is a view taken as on the plane indicated by the line 12—12 of Figure 5 looking in the direction of the arrows. Figures 11 and 12 illustrate the mechanism for transversely winding or twisting the yarn prior to the yarn being coiled upon the spool and in said figures the parts are shown on a somewhat larger scale than in Figure 5.

The leather from which the yarn is to be made may be of any suitable kind, for instance calf's, cow's, sheep's or any other kind of leather. It is first brought to uniform substance, that is to uniform thickness, as 110 by shaving or splitting, as is clearly indicated in Figure 2. The pieces are designated

by A and the ends thereof are cut preferably parallel with each other and are beveled, as shown at a—a in Figure 2. The pieces are arranged end to end and the adjacent ends 5 of adjacent pieces are then connected or stuck together by suitable cementing material so as to form a comparatively wide long band or strip B. This long band or strip B while of uniform thickness is not necessarily of uniform width and is also preferably much wider than is desired or than can be employed directly in the making of the yarn. It can, however, be readily severed or cut into a number of narrow strips 15 which are suitable for the purpose. It will here be remarked, however, that it is advisable to form the narrow strips in this manner rather than to form each narrow strip by itself from strips which are brought 20 to the desired width prior to being joined and I purposely form the wide strip or band as a preliminary to the forming of the narrow strips.

Mechanism which I have found suitable 25 for the purpose of cutting the wide strip or band into the small narrow strips comprises a pair of cooperating grooved slitting rolls C and D which are clearly indicated in Figures 3 and 4. The band B before 30 being slitted is indicated at the right hand side of Figure 4 and the narrow strips formed as the result of the slitting operation are designated by e f g h j; these narrow strips are coiled or wound upon spools 35 E. When the narrow strips are thus spooled they are ready to be employed in the manner shown in Figure 5—provided the leather thereupon is sufficiently damp and if not sufficiently damp it must be dampened prior 40 to being twisted.

The machine may be considered to comprise a main frame 1 supporting a winding head 2—sometimes herein called a twisting head—which carries the spool of leather, a 45 transverse rolling mechanism 3 and a mechanism 4 for spooling or coiling the yarn. The winding head 2, the transverse rolling mechanism 3 and spool mechanism 4 are all driven from the motor M by means of suitable belts and gearing, as will hereinafter 50 more fully appear. Upon the frame 1 there is also carried a spool holder 5 upon which a spool carrying a thread or strand 6, that can be relied upon to provide a core for the 55 yarn, is placed, when the yarn is to comprise a core.

The winding head 2 has a tubular member 7 which provides a hollow shaft for the head and this shaft is mounted in a suitable bearing, as 8. On the shaft there is placed the spool E carrying a long narrow leather strip and on this hollow spindle or shaft there are also suitably carried a central guide-way 9 and an inclined guide-way 10, both of which rotate with the spindle or shaft. The leather

strip from the spool passes over the inclined guide-way 10 toward the entrance end or throat of the central guide-way 9. The winding head or twisting head 2 is driven from the motor M by the following train; 70 to wit, pulley P on the motor shaft, belt 11, pulley 12 on shaft 13, said shaft 13, pulley 14 which is on the shaft 13, belt 15 and pulley 16 on the tubular member or shaft 7 of the twisting head 2.

Disregarding for the time being the transverse rolling mechanism 3, it will be seen that the yarn is then, or shortly after being formed, coiled upon a spool 17 carried on an arbor or shaft of the spool mechanism 4. In 80 the operation of the machine the thread 6 passes through the tubular member 7 to the spool 17, if a thread is to be employed, and as the twisting head 2 revolves, the strip of leather from the spool E passes over the 85 inclined guide-way 10 and is deposited in such a manner that it is wound in a cylindrical or spiral path about the core; in other words, the strip of leather takes the form of a cylindrical helix and the central guide-way 90 9 determines the diameter of the product which passes through it, that is, the diameter of the product is not larger than the inner diameter of the central guide-way 9.

It is not necessary, however, to employ 95 the core, although the same is advisable, because the leather from the spool E will be deposited in the same manner even though the core is not employed. In order that the yarn may be truly circular and smooth, and 100 given a permanent set the transverse rolling means is provided, as at 3. This transverse rolling means comprises a pair of opposed platens arranged so that when they are in engagement with the yarn one of the platens 105 is moving in one direction while the opposing platen is moving in a reverse direction but at substantially the same speed. These platens are in engagement with the yarn only when they are moving on what may be 110 called a forward stroke; on the reverse stroke they are not operatively engaging the yarn. The transverse rolling mechanism is shown in plan in Figure 5 but vertical views thereof are shown in Figures 11 and 12. 115 The platens may be referred to as upper and lower platens designated respectively as 18 and 19. The rolling mechanism 3 has uprights or standards 20. The lower platen has screw-connections at 21, 21 to a rod 22 which is slidably mounted in the uprights or standards 20 and by this rod one longitudinal edge portion of the platen is supported, as is clearly shown in Figure 11. The other edge of the platen is supported by a stationary rod 23 that is carried by the uprights or standards 20 and the platen 18 is slidably mounted on this rod. A cross-bar 24 is carried at the upper ends of the uprights or standards 20 and provides a bearing for a 120

125

130

vertically movable rod 25. A yoke 26 is carried at the lower end of said rod 25 and in the depending arms 27 of the yoke there is carried a slidably mounted rod 28. The upper platen 19 is screw-connected at 29, 29 to this rod so that one edge portion of the platen is supported by the rod, as clearly shown in Figure 11. The opposite edge portion of the upper platen is carried by a fixed rod 30 which is in the depending arms 27 and said portion of said platen is slidably mounted on said rod. It will therefore be seen that when the rods 22 and 28 are reciprocated the platens which are respectively connected thereto will consequently be reciprocated. A means is provided for effecting this reciprocation. This means comprises cooperating gears 31 and 32, the former of which is connected to and driven by the shaft 13 heretofore referred to. The shaft 13 extends sufficiently far to carry and drive a crank 33. One end of a link 34 is connected to the crank-pin 35 thereof while the other end of the link is connected at 36 to the rod 28 to which the upper platen 19 is connected. The gear 32 drives a shaft 37 which in turn carries a crank 38. A link 39 has one end thereof connected to the crank pin 40 of the crank 38, while the other end of the link is connected at 41 to an end of the reciprocating rod to which the lower platen is connected. It will, therefore, be seen that as the shaft 13 turns the cranks just referred to will be revolved with the consequent result that the platens 18 and 19 are reciprocated. The crank pins are positioned relative to each other so that when the platens are in operative engagement with the yarn the platens are moving in opposite directions but at relatively the same speed.

The upper platen has been described as being carried on the yoke 26 which is at the lower end of the vertically slidable rod 25. This rod 25 is under the control of a lever 42 fulcrumed at 43. This lever is slotted, as at 44, and in the slot there enters a pin 45 extending from a collar 46 that is secured to the upper end of the rod 25. A compression-spring 47 is arranged between the cross-bar 24 and the collar 46. The movable end of the lever 42 engages a cam 48. The shaft 13 and gear 31 revolve in the direction of the arrow Z. The cam 48 is constructed and arranged so that when the upper platen is moving in the direction of the arrow X and when the lower platen is moving in the direction of the arrow Y the upper platen will not be pressing against the yarn; in other words, will be in an inoperative position, but so that when the platens are each moving in the reverse direction the yarn will be engaged by them and will be transversely rolled and to a certain extent twisted by the platens—the twisting effect being due to one portion of the yarn being held against

torsional movement of the spool 17 while the yarn next to be spooled is receiving the torsional motion or twist and in a direction to tighten the yarn.

The spooling mechanism 4 is driven 70 through the following train of mechanism, to wit, the bevel gear 49 which is on the shaft 37 that drives the crank 38 from the gear 32, the bevel gear 50, shaft 51, pulley 52, belt 53, pulley 54 and friction disks 55 75 and 56, the latter disk being connected to the arbor or shaft that carries the spool 17. The spool 17 is clamped on the shaft. In order that inequalities of tension may be taken care of and a required slip in the driving 80 mechanism permitted, a compression spring is provided at 57 to regulate the pressure between the friction disks 55 and 56. The compression of this spring is controlled by an adjusting nut 58. Manifestly, any slight 85 pull which may be the result of the platens seizing the yarn can be taken care of by this arrangement; or, to state the same thing, in a reverse way the spool will wind the yarn only as it is allowed to do so and this without imparting any undue strain to the yarn. 90

From what has preceded it will be manifest that the winding head deposits the long narrow strip—as e, see Figures 4 and 6—from spool E in a helical path, or in other 95 words, winds the strip so as to form a circular product, to wit, a yarn (see Figure 7); that this circular product, to wit, a yarn, is ironed and transversely rolled between the platens, and that there is a slight twisting 100 of that portion of the yarn between the platens—or transversely rolling mechanism 3—and the spool 17 as the rolling operation is taking place. The result of the series of steps herein described is to produce a product 105 of regular diameter, smooth and uniform and with a permanent twist or set in the leather.

It has heretofore been indicated that it is advisable to moisten the leather in the strip prior to being twisted. This may be accomplished, for example, by applying a wet sponge to the leather strip as it is being twisted; or other means of dampening might be employed, for example, it might be advisable to soak the leather on the spool prior to bringing the spool into position for the twisting operation. 110

If desired a number of strips could be fed to the winding or twisting head and simultaneously wound or coiled so that they would together form a single yarn of several plies where extra strength, for example, is required. With such a winding head, however, the number of inclined guideways 115 120 would correspond to the number of narrow strips employed.

The core, if used, can be made of such material as cotton, silk, linen, leather, etc., or any other suitable material. Instead of 130

making the narrow strips in the manner described they could be made by circular cutting, but if the leather were cut into circular form it should be straightened by dampening and stretching. In some instances it would be possible to perform the stretching during the spinning and twisting operation. The yarn, or thread or strand of leather as it may be called, may be treated by any of the usual methods employed to strengthen and soften the leather and when the yarn or thread is properly spooled it is ready for weaving, if it is desired to employ the yarn for such purpose. The yarn or thread of leather can be employed either as a warp, or as a filler, or both, or can be combined with other material and woven into a fabric made either wholly of or comprising as an essential part thereof a leather yarn. The yarn may be given any desired color before weaving, or if it is desired a fabric made from the yarn can be colored after weaving.

A fabric made of leather yarn is of such a character that it can be made smooth and strong and can be softened and rolled or twisted, if desired, since the nature of the leather is in no way changed and can be put through any of the processes to which leather in the original state can be subjected. The leather yarn may be woven into a fabric of practically any length desired, for example, it can be woven long enough to make a belt adapted for the transmission of power should such a construction be desired. A fabric made of the leather yarn is clearly indicated in Figures 8, 9 and 10. It will be noted, however, that where it is desirable to have the fabric substantially smooth and flat this can be accomplished by pressure, as by calendering, and in this way the "high" spots of the weave will be pressed down, as is indicated in Figures 8 and 9. Figure 10 indicates the appearance of the fabric prior to the calendering.

In the manufacture of yarn in the manner herein described a large number of pieces of leather now wasted or sold for a very nominal figure can be utilized, and as none of the peculiar properties of the leather have been destroyed the resulting product, to wit, the yarn, can be used to advantage in many places and for many purposes.

This application is in many respects a continuation of and in other respects a substitute for my application Serial No. 67337 filed December 17, 1915 entitled "Leather manufactures."

The improvements herein set forth are not limited to the precise construction and arrangement shown and described for they may be embodied in various forms and modifications without departing from the spirit and scope of the invention.

What I claim is:

1. The method of forming leather yarn, consisting in taking a narrow strip of split leather, moistening the same, twisting the moistened strip to form a circular product, and finally subjecting the yarn to an intermittent transverse rolling and pressing operation.

2. The method of forming leather yarn, consisting in taking a narrow strip of split leather, moistening the same, twisting the moistened strip to form a circular product and finally subjecting the yarn to an intermittent transverse rolling and pressing operation to form a yarn substantially circular in cross section.

3. A leather yarn comprising a core, and twisted, leather strips surrounding the same.

4. A woven fabric comprising as an essential part thereof a leather yarn made up of a core and twisted leather strips surrounding said core.

This specification signed this 14th day of October, A. D. 1918.

WILLIAM M. CAVANAUGH.
